JAMES H. PIERCE, OF BAY CITY, MICHIGAN, ASSIGNOR, BY MESNE ASSIGNMENTS, TO
GENERAL MACHINERY COMPANY, OF BAY CITY, MICHIGAN, A CORPORATION.

INTERNAL-COMBUSTION ENGINE.

No. 801,366.

Specification of Letters Patent. Patented June 23, 1908.

Application filed November 8, 1906. Serial No. 342,483.

To all whom it may concern:

Be it known that I, JAMES H. PIERCE, citizen of the United States, residing at Bay City, in the county of Bay and State of Michigan, have invented certain new and useful Improvements in Internal-Combustion Engines; and I do hereby declare the following to be a full, clear, and exact description of the invention, such as will enable others skilled in the art to which it appertains to make and use the same.

My invention relates to internal combustion engines of the two-cycle type, rear compression. Heretofore, many attempts have been made to improve engines of this type, in order that they may compare favorably with the four-cycle engine. Especially is this so in those two-cycle engines wherein the idle stroke of the piston operates to draw the succeeding charge into a closed crank case past an atmospherically actuated valve, but no one, so far as I am aware, has devised any means for perfecting the operation of this inlet valve. Hitherto such inlet valve has fluttered or chattered on its seat when the engine is at high speed, owing to the extreme rapidity of reciprocation of the piston, and while an operative motor was attained, it was of comparatively low speed. At high speed, the motor was not wholly satisfactory, owing to the fact that the valve was neither on nor off its seat at any one time, and as a consequence a sufficient charge was not supplied to the cylinder.

This invention is, however, designed to relieve this objection, and by so doing to raise the efficiency of the two-cycle motor. It will also be noted that in a three-port engine the duct forming the passage from the two sides of the piston to charge the cylinder, makes an additional space to be filled by air when the piston is nearly to the end of its stroke. When the lower end of this passage is uncovered, it causes a reduction of pressure in the crank-case by reason of its requiring filling, and the reduction in speed of the piston causes no additional opening of the suction valve. To insure a greater supply of air to the crank-case just before the piston gets to its upper limit of movement than at any other time, I have a pipe leading from the inlet pipe, behind its suction valve, to the cylinder, and its end entering the cylinder is so disposed that it is uncovered by the piston on its upward limit of movement

and is placed in a line about midway between the two ends of the duct or passage in the cylinder. In accomplishing this result, I employ several novel features and combinations, which will be more fully described 60 hereinafter and particularly pointed out in the claims.

In the accompanying drawings, Figure (1) is a vertical cross-sectional view of a motor equipped with my invention, the piston occupying the position immediately prior to the explosion of the charge, and Fig. (2) is a similar view showing the position of the piston at the lowest point of its working stroke.

(A) is a cylinder of any approved construction and provided with a closed crank case (1), a hollow piston (2) reciprocating in the cylinder being connected by means of a piston rod (3) with a crank shaft (4). The head of the piston may be provided with a deflector (5) and the shell of the piston is equipped with an aperture (6) adapted to register with the lower port (7) of a U-shaped mixture passage (8) conveniently formed in the cylinder wall, or otherwise as preferred. This aperture (6) fully registers with the lower port (7) only when the piston has attained its outward limit of movement in its working stroke, at which time the upper port (9) of said mixture passage is in free communication 80 with the cylinder and opposite the deflector (5), to admit the charge to the cylinder. The return stroke of the piston then compresses the charge which is fired and the piston makes another working stroke. 90

The exhaust port (10) is preferably located opposite the inlet port (9) and at a slightly higher level than such inlet port, in order to permit the escape of the larger portion of burned gases prior to the admission of the new charge. 95

The mixture intake port (11) communicates with the crank casing and is controlled by a suitable check valve (12), a spring (13) tending to seat the valve at all times to close 100 the port, a pin (14) being located in advance of the valve to limit its inward or opening movement. A carbureter (15) is connected to the port and communicates with the crank case when the valve (12) is opened. 105

I have thus far described a structure wherein a charge from the carbureter may be admitted to the crank case where it is compressed on the working stroke of the piston and escapes through aperture (6) and pas- 110

sage (8) to the cylinder, when the piston has about reached its lowest limit of outward movement. Such an arrangement, however, will permit the valve (12) to flutter on its seat when at high speed, without correctly performing its duty and in order to allow the valve to become seated during the idle or compression stroke of the piston and prior to the time when the piston completes such stroke, I provide a means now to be described, such means also permitting the entrance of a full charge into the crank case of the motor, which was only indifferently attained otherwise owing to the fluttering of the valve and the great rapidity of reciprocation of the piston.

The pipe (17) leads from the pipe entering the crank-case passing from behind the suction valve therein to a point in the cylinder 20 below the exhaust (10), and having its inlet (16) into the cylinder placed in a line substantially equi-distant from the ends of the mixture-passage (8).

The effect and operation of this construction is as follows—Assuming that the piston has reached the limit of its working stroke and is about to make its inward or compression stroke, the exhaust port (10) will have been uncovered to release the products of 25 combustion or the spent charge and directly thereafter the inlet port (9) will have been uncovered by the further movement of the piston to admit the new charge, the aperture (6) registering with port (7) to permit the compressed mixture to pass through the passage (8) and into the cylinder against the deflector (5) scavenging the cylinder in the usual manner.

On its instroke, the piston will first cover 40 the exhaust port (10) and practically simultaneously therewith, will cover the port (7) to prevent the entrance of further mixture, the free inlet (16) being covered by the piston from a time shortly after it has started 45 on its working stroke until just before it reaches the limit of its compression stroke. The instroke of the piston will immediately tend to create a vacuum in the crank case which is at once relieved by the opening of 50 the check valve (12) under atmospheric pres-

sure, permitting the entrance through port (11) into the crank case of a charge from the carbureter (15). As the piston compresses the mixture in the cylinder on its instroke, it will continue to draw in a fresh charge 55 through port (11) until the piston nears the limit of its instroke, when it uncovers the lower end of the passage 8 then the passage 8 is filled, but reduces the pressure in the crank-case, and as the piston reaches the limit of its 60 stroke the free inlet (16) is uncovered and mixture is thereupon admitted through such inlet to the exclusion of the intake port (11) for the reason that the vacuum will be relieved by the mixture drawn from the easiest 65 source, and the free inlet (16) is not obstructed by a check or other valve, consequently the mixture will pass into the motor through inlet (16) and permit the spring (13) to fairly close the port (11). Of course, this 70 operation takes place in a fraction of a second when the engine is driven at high speed.

It will be observed that a combustible mixture enters through both the intake (11) and the inlet (16), thereby insuring a full 75 charge to the crank case and to the cylinder.

Having thus fully disclosed my invention, what I claim as new is—

A motor having a cylinder a piston and a closed crank case, the cylinder having a passage with its ends in the cylinder and adapted to have its ends alternately uncovered on the limits of movement of the piston, a carbureter having its outlet connected to a pair of pipes, one pipe entering the crank case and having a suction valve therein, and the second pipe passing from behind the suction valve to the cylinder and entering the cylinder at a point approximately in a line equi-distant between the ends of the passage in 80 the cylinder, the end of the piston uncovering the outlet of the second pipe only at its upward limit of movement.

In testimony whereof, I affix my signature in presence of two witnesses.

JAMES H. PIERCE.
